G. M. WILLIAMS,
MAGAZINE CHARGING APPLIANCE FOR EYELETING AND LIKE MACHINES.
APPLICATION FILED JAN. 3, 1916.

1,358,044.

Patented Nov. 9, 1920.

UNITED STATES PATENT OFFICE.

GEORGE M. WILLIAMS, OF ELIZABETH, NEW JERSEY, ASSIGNOR TO P. LORILLARD COMPANY, OF NEW YORK, N. Y., A CORPORATION OF NEW JERSEY.

MAGAZINE-CHARGING APPLIANCE FOR EYELETING AND LIKE MACHINES.

1,358,044.

Specification of Letters Patent.

Patented Nov. 9, 1920.

Application filed January 3, 1916. Serial No. 69,844.

To all whom it may concern:

Be it known that I, GEORGE M. WILLIAMS, a citizen of the United States, residing at Elizabeth, in the county of Union and State of New Jersey, have invented new and useful Improvements in Magazine-Charging Appliances for Eyeletting and like Machines, of which the following is a specification.

- 10 This invention relates to certain novel and useful improvements in a device which is adapted to be employed in filling or supplying magazines or other containers with such articles as are intended to be dispensed
- 15 or fed from the magazine and has particular application to a filler device designed to be used in replenishing the supply of magazines for eyelets, staples, rivets and other fastening devices.
- 20 In the embodiment of the invention shown herein I have illustrated my device as employed for the purpose of feeding or supplying eyelets to an eyelet magazine, but I wish it to be understood that the invention
- 25 is not limited in its useful application to this particular purpose, as it may be employed in any connection, or under such circumstances as may be deemed advisable, or found advantageous.
- 30 In carrying out my invention it is my purpose to provide a device of this character through the embodiment of which a magazine, chute or other holder or container may be conveniently supplied with the de-
- 35 sired quantity of eyelets with a minimum expenditure of time. Furthermore, I propose to provide a device wherein the bulk of the eyelets may be indiscriminately thrown or placed in a supply reservoir from
- 40 which leads a discharge chute, said eyelets as they pass into the discharge chute being caused to assume a pre-determined arrangement or position so that the eyelets will leave the chute in orderly arrangement and
- 45 be supplied to the magazine in a row or rows.

Furthermore, another object of the invention is the provision of means within the reservoir through the medium of which the eyelets will be caused to assume a particular

and predetermined position as they enter the discharge or feed chute by which they are conveyed to the magazine.

Furthermore, I propose to provide my device with a sectional or removable chute so 55 that when desired a section of the chute, which has been filled with a row of the eyelets, may be disconnected from the reservoir and carried to the magazine and applied to the latter, this being a matter of convenience 60 when the entire device including the reservoir cannot be conveniently manipulated or positioned relative to the magazine of the eyeletting machine.

A further object of the invention is the 65 provision of means for locking or cutting off the flow of the eyelets through the discharge end of the permanent chute section, when the detachable chute section is removed therefrom, and the provision of 70 means in the nature of a stop device for controlling the escape of the eyelets from the detachable section of the chute, whether said detachable section be in its attached or detached position.

It is also my aim to provide a device of 75 this character which will embody the desired features of simplicity, efficiency and reliability, and which embodying as it does but relatively few parts, may be manufactured and marketed at a comparatively low 80 cost.

With the above recited objects and others of a similar nature in view, my invention consists in the construction, combination 85 and arrangements of parts set forth in and falling within the scope of the appended claims.

In the accompanying drawings,

Fig. 1, is a perspective view of the device embodying my invention.

Fig. 2, is a detail view in elevation of a portion of the eyelet reservoir and showing ports for the eyelets leading from the reservoir to the feed chute, said chute being 95 shown in cross section.

Fig. 3, is a vertical sectional view taken through a portion of the reservoir in the upper section of the feed chute which is connected with the reservoir, this view illus- 100

trating the lock for preventing the eyelets entering the removable or detachable chute section.

Fig. 4, is a top plan view of the reservoir 5 with the cover removed, a portion of the side wall of the reservoir adjacent the chute being shown in section.

Fig. 5, is a top plan view of the pivoted stop at the bottom of the chute adapted to 10 control the feed of the eyelets from the chute to the magazine.

Fig. 6, is a vertical sectional view taken through the lower portion of the feed chute and showing the latter as connected with 15 the top end of a magazine chute, the latter also being shown in section.

Referring now to the accompanying drawings in detail the numeral 1, indicates a suitable base or bed plate carrying the vertical standard 2, the upward end of which is provided with a socket member 3, which has formed integral therewith the platform 4. This platform carries a reservoir 5 as shown in Figs. 1 and 3. Mounted on this platform 25 4 is the eyelet reservoir which is indicated as an entirety by the letter R, said reservoir including an eyelet containing section 5 and a cap or cover 6 fitting thereover. The reservoir is preferably circular in its general contour, the cap 6 having a flange 7, which fits over the circular side wall 8 of the body or container section of the reservoir. The cap section is further provided with a segmental slot or opening 9 in its top wall; this opening being adapted to be closed by a segmental plate 10 pivoted at 11 to the top wall and constituting a door for the slot 9, this plate 10 having an upturned lip 12, forming a finger grip for swinging the plate 40 to cover and uncover the opening. Of course it is to be understood that the eyelets are preferably poured into this slot or doorway 9 in bulk. At suitable intervals I attach to the side of the cap spring clips 13, the 45 lower ends of which are provided with shouldered heads 14 adapted to fit beneath the bottom of the reservoir and thus lock the cap in position. Fitted to revolve in the bore 16 of the socket member 3 of the standard 2 is one end of a shaft 17, the opposite end of said shaft projecting through an aperture 18 in the top wall of the cover of the reservoir and has pinned to its outer end a suitable 50 crank 19 by means of which the shaft may be revolved by hand, a bearing collar 20 being mounted on the shaft between the crank and the top wall of the reservoir. The portion of this revolving shaft within the reservoir is provided with a hub 21 from which 55 radiate the tubular arms 22, these tubular arms forming sockets for the brushes 23, the outer ends of the brushes being adapted to swing around or bear against the inner wall of the flange 8. It will thus be seen 60 that within the reservoir is located a revolv-

ing agitator or sweep for the eyelets shown at E, this sweep including a revolving spider and a series of brushes carried thereby. Formed in the circular wall or flange 8, of the containing section of the reservoir are the spaced eyelet ports 24, which are narrower at the top than at the bottom, so that the eyelets shown at E can only escape through the ports, shank end upward. Located intermediate the ports 24 and extending outward is a long V shaped tongue 25 which comes to a point at its outer end, this tongue projecting above and parallel with the bottom 26 of the chute section 27, which is preferably permanently connected with 75 the container section of the reservoir in line with the eyelet ports thereof. This chute section 27 in addition to the bottom 26 is made up of the side walls 28 which flange toward their lower end and inwardly extending top flanges 29 carried by these side walls. By reference to Fig. 1 it will be seen that the V-shaped tongue 25 divides this chute section 27 into two inclined eyelet guide-ways 30, which converge and meet in 80 a common guide-way 31 at the bottom of the chute section. It will further be noted that the circular wall 8 of the reservoir has a segmental slot 8' therein, which communicates with or leads to the eyelet ports. This slot performs an important function, for as 85 will be seen by reference to Fig. 4, as the indiscriminately arranged mass of eyelets are swept around in the reservoir, the disk-like heads of certain of the eyelets will be pushed into and through this slot, and consequently these eyelets will be properly positioned shank upward and will be guided to the eyelet ports through which they may pass to 90 the chute. As will be seen slot 8' is located 95 in advance of and leads directly into the entrance ports 24, being in open communication with both ports, the latter being located at the lower portion of the reservoir. When, therefore, the agitator sweeps the bulk mass 100 of eyelets around the reservoir, more or less of such eyelets will be positioned in proper relation to enter slot 8', although still forming part of the mass, and are free to pass out 105 of such slot should the action of the mass be such as to force this action, thus preventing 110 an actual choking of parts. In addition, the eyelets are free to advance in the slot toward the outlet under the agitator and mass action, the eyelets in the slot thus being selected 115 from the mass in advance of actual passage from the reservoir. And since both entrances 24 are in open communication with this slot the selected eyelets may enter either 120 channel, thus better assuring that the selected eyelets will pass from the reservoir and not be returned under the sweeping action. It will further be noted that the eyelets passing down the slots or guide-ways 30 must 125 necessarily travel shank end up, for they 130

cannot leave the reservoir in any other position, as will be seen by reference to Fig. 4. The detachable end of the chute is shown at 32 and is adapted to be slipped into the lower 5 end of the coupling member 33 carried by the lower portion of the permanent section of the chute. The inturned longitudinal flanges 34, form a slot 35 extending longitudinally of the chute from end to end and 10 through which slot the upturned shank of the eyelets may project, as is clearly shown in Fig. 1, the head of the eyelets bearing against the bottom of the chute as the eyelets pass down the latter. As the detachable 15 chute section 32 communicates with the permanent chute section, so as to form practically a continuation thereof, it will be seen that the eyelets passing down the two converging slots in the permanent section 27 of 20 the chute will be guided into the detachable section of the chute and will pass down the latter and being unimpeded will be discharged through the lower end of the chute shown at 36, and which end is connected with 25 an enlarged chute section 37 of the size and shape to conform and fit over the top end of the magazine chute M, a spring slip c carried at the top of the magazine M being adapted to bear against the back of the enlarged chute section 37 and hold the latter 30 locked to the magazine chute, as is clearly shown in Fig. 6.

At certain times it may be found desirable 35 to cut off the flow or feed of the eyelets from the discharge end of the detachable chute section as when, for instance, a magazine has been filled without using up all of the eyelets in the detachable chute section at the 40 filler device, and to accomplish this any suitable stop or cut may be employed. For instance, at the lower end of the detachable chute section I may fasten a plate 38, and pivot to this plate, as at 39, a stop plate 40, having a tapered end 41, which projects 45 through a slot 42 in the side wall of the chute so that the tapered end or tongue 41 of this stop plate may be swung transversely of the chute to form a stop for the descending eyelets, or may be swung to one side, as shown 50 in the dotted lines in Fig. 5, to permit the continued passage or escape of the eyelets. The location of stop 40 on chute 32 is of particular advantage where this chute simply acts as a transfer means and is detached, stop 55 40 serving as an end abutment to close the channel so that the chute may be carried about in an inclined position and maintaining the procession of eyelets in proper relation without requiring closing of the channel by fingers of the person carrying the chute. Likewise, I make provision for obstructing the discharge end of the permanent chute section 27 when the detachable chute section 32 is removed therefrom, this being 60 advisable to prevent the falling out or escape of any eyelets which might be in the slots of the permanent chute section at the time the detachable section is uncoupled therefrom. To this end I provide the bottom wall of the coupling member with a slot 43, which opens through the front edge of the bottom and is adapted to receive the hooked end 44 of the latch 45, which is pivoted at its opposite end as at 46 to a bracket 47 carried by the coupling member. A spring 75 48 normally tends to seat the hooked end of the latch 45 in the slot, thus causing such end to close the passage through the bottom of the coupling member. However, when the detachable chute section is coupled with 80 the coupling member, as shown in Fig. 1, the upper end of the detachable chute section will strike against the projecting end of the hook 44 and force the latter out of the slot, the adjacent upper end portion of the 85 detachable chute section covering the slots as shown in Fig. 1. The instant, however, that the detachable chute section is itself uncoupled, this latch or hook will spring back into position, as shown in Fig. 3 and block 90 the discharge of the eyelets.

From the above description, taken in connection with the accompanying drawings, the construction and operation of my invention will be readily apparent. 95

Assuming that it is desired to fill the eyelet magazine M with eyelets taken from the reservoir, this may be accomplished by the operator simply turning the crank 19 and causing the revolving brushes to sweep the eyelets around in the reservoir. In this motion, as shown in Fig. 2, the heads of certain of the eyelets being projected through the slot 8', are thus pushed and guided to the eyelet ports 24 through which they pass 100 head down and shank up, into the permanent chute section, passing down the latter into the detachable chute section, as the latch 45 at this time is in inoperative or non-stopping position, by reason of the upper end of the detachable section of the chute having forced the latch outward. The pivoted stop 40, however, at the bottom of the detachable section of the chute lies transversely or across the chute, as shown in Fig. 1, so as to catch 105 the eyelets. When the chute has been filled with a row of the eyelets, the detachable section may be pulled from the coupling 33 of the permanent section, and the instant this detachment takes place, the latch 45 will 110 spring into position to block the further escape of eyelets from the permanent section of the chute. The operator may now carry the detachable chute section which is filled 115 with the eyelets to wherever the eyeleting machine is located, and may apply the unlatched chute section 37 to the top of the magazine, as shown in Fig. 6, and swing the stop 40 to the position shown in the dotted lines in Fig. 5, thereby permitting the eye- 120 125 130

lets to escape from the detachable chute section and into the magazine.

If desired and convenient, the magazine chute may be connected with the large chute section 37, without removing the detachable chute section from the permanent chute section, so that the eyelets may be fed in a continuous steady stream direct from the reservoir into the magazine.

10 From the above description taken in connection with the accompanying drawing, it will be noted that I have provided an exceedingly simple yet efficient device for loading a magazine with eyelets or like articles 15 without the loss of time, and also assuring that the eyelets or other articles will be properly positioned in the magazine.

While I have herein shown and described one particular embodiment of my invention, 20 I wish it to be understood that I do not confine myself to all the precise details of construction herein set forth by way of illustration, as modifications and variations may be made without departing from the spirit of 25 the invention or exceeding the scope of the appended claims.

What I claim is:

1. In a device of the class described, in combination, a reservoir for fastening members, a permanent chute section associated therewith, a detachable chute section, a coupling member associated with the permanent chute and adapted to receive one end of the detachable chute, latch means associated 35 with the coupling member forming a stop for the fastening members, said latch means being operated by the detachable chute to throw it into or out of operative position, to either stop or permit the passage of the fastening members, and a rotatable agitator 40 operable to deliver the fastening members to the chute.

2. In a device of the class described in combination, a reservoir for fastening mem-

bers having a peripheral slot therein, a permanent chute section associated with the reservoir and communicating with the slot, a detachable chute section, a coupling member associated with the permanent chute section and adapted to receive one end of the detachable chute, latch means associated with the coupling member forming a stop for the fastening members, said latch means being operated by the detachable chute to throw it into or out of operative position, to either stop or permit the passage of the fastening members, and a rotatable agitator operated to push the fastening members along the peripheral slot and to deliver such fastening members to the chute. 60

3. In a device of the class described and in combination, a reservoir for receiving fastening members, a permanent chute leading from said reservoir, means for delivering members to said chute individually to form a procession, a chute detachably connected to said permanent chute and having a slot in the side wall thereof, a stop device carried by the permanent chute and operative in the member travel path of the chute, 65 said detachable chute controlling the activity of the stop device, and means carried by the detachable chute and entering through said slot in the walls of the chute for controlling the egress of members from said chute, said means being normally out of the path of progression and movable thereinto at will, whereby said detachable chute may serve as a transfer means for the members carried thereby. 70

In testimony whereof I have hereunto set my hand in the presence of two subscribing witnesses.

GEORGE M. WILLIAMS.

Witnesses:

WILLIAM B. LEONARD,
